UNITED STATES PATENT OFFICE.

CHARLES M. HEETER, OF BUTLER, PENNSYLVANIA.

WELL-SWABBING MECHANISM.

1,098,320.

Specification of Letters Patent. Patented May 26, 1914.

Application filed November 20, 1913. Serial No. 802,080.

To all whom it may concern:

Be it known that I, CHARLES M. HEETER, a citizen of the United States, and resident of Butler, in the county of Butler and State 5 of Pennsylvania, have invented certain new, and useful Improvements in Well-Swabbing Mechanism, of which the following is a specification.

The primary object of this invention is 10 to provide means for utilizing the gas pressure of a gas-producing well for ejecting, or for assisting in ejecting, the water that is ordinarily withdrawn solely by the upward pull of the swab-forming piston or 15 plunger. With present methods and apparatus, the gas pressure is not ordinarily available for assisting in this work, being excluded from the tubing by the accumulated water, the latter forming a seal 20 around the inlet of the swabbing tube. The invention herein provides a valve-controlled gas inlet for the tube which is spaced above the water collecting zone, so that when the pressure is sufficient the admitted gas will 25 operate to either blow the swab-raised water upwardly and out of the tube, or if the pressure is insufficient for this it will at least assist the water-lifting upward stroke of the swab and to that extent decreasing the 30 power that would otherwise be required to raise the swab.

A further feature of the invention is the provision for admitting gas to the space between the well tube and the swabbing tube 35 throughout a considerable vertical area—an area above that heretofore open for such admission, thereby facilitating the upward flow of gas, and at the same time rendering such maximum flow available for the water- 40 ejecting operation.

In the accompanying drawings, Figure 1 is a vertical section of a portion of a gas well embodying the improvements of the present invention. Fig. 2 is a sectional detail 45 of the valved trap for the swabbing tube.

Referring to the drawings, 2 designates the swabbing tube of a deep well, primarily a gas-producing well, and 3 is the piston or 50 plunger-like swab which may be operated therein by sucker rods 4 or other suitable means. Swab 3 is here shown of the form illustrated and described in my Patent No. 1,021,600, granted March 26, 1912, to which 55 reference may be made for its detailed operation. It will be understood, however,

that the present invention may be utilized in connection with swabs of various forms, and hence is not limited or restricted to the particular type shown. In Fig. 1, the swab 60 is shown on its down stroke with its top outlets 8' open for the upward passage of fluid, as described in the above mentioned patent.

Swabbing tube 2 is provided with the 65 usual upwardly opening foot or standing valve 5, from which a perforated anchor tube 6 may extend to the bottom of the well. At a suitable distance above the standing valve a section 7 of the swabbing tube 70 through which swab 3 operates is confined between the coupling heads or sockets 8, and this tube section 7 is open laterally at 9 for the admission of gas. Tube section 7 is inclosed by casing 10 spaced therefrom and 75 secured to heads 8, as shown. This casing is formed with a lateral inlet 11 which is normally closed by the free portion of the leaf spring 12, the latter secured to the inner side of casing 10, as indicated at 12'. Inlet 80 11 is located above the portion of the well in which water ordinarily accumulates, and spring-closure 12 is preferably of sufficient strength to remain closed against relatively low external gas pressure, say four or five 85 pounds, as lower pressures would not be of much assistance in the operation. When the swabbing is to proceed, swab 3, acting as a pump piston, is reciprocated beneath the gas inlets 9 until the column of water 90 reaches the latter. If the gas pressure is sufficiently strong, spring 12 is held open and the gas enters and passes upwardly through the swabbing tube, and when the column of water reaches such strong flow of 95 gas it is blown or lifted thereby upwardly through and ejected from the swabbing tube, the gas continuing to thus blow out the water so long as the swab continues to replenish the water column above inlets 9. 100

If the gas pressure is too low to raise the water, or any considerable portion thereof, the swab is reciprocated sufficiently to collect thereabove a column of water of desired height, the water pressure holding 105 spring 12 closed against inlet 11. Then on the final water-lifting stroke or travel of the swab it passes above inlets 9, and closure 12 being relieved of the water pressure it may open under the external gas pressure, 110 and the pressure thus communicated to the tube beneath the swab operates to assist the

upward movement of the latter and to that extent decreases the force or power from above to withdraw the water-laden swab.

The invention may be utilized under 5 widely varying conditions prevailing within the well. In the present adaptation, the swabbing tube 2 is shown within a string of tubing or casing 13, the latter provided with a packer 14 for shutting off water that 10 may accumulate in the portion of the well thereabove. The packer is of usual construction, for which no novelty is claimed. Portion 13' of tubing 13 beneath the packer is 15 preferably perforated for a considerable distance vertically, as indicated at 15, the lower perforations serving to admit water, and the upper perforations admitting gas to the space between tubes 2 and 13. Without the upper perforations the gas might otherwise 20 be closed off by water accumulation at the exterior of tubing 13' and prevented from being available in the water-lifting operation above described. Furthermore, by thus admitting gas to the upper portion of that 25 part of the well tubing beneath the packer, the flow of gas from the well is not so liable to be smothered or interrupted by accumulated water as when it can enter only at or adjacent the lower portion of tubing 13'.

30 I claim:—

1. A swabbing tube for deep wells having a valved fluid inlet in that portion of the tube through which the swab operates.
2. A swabbing tube for deep wells having 35 a lateral fluid inlet in the portion thereof through which the swab operates, and an inwardly opening closure for the inlet.
3. A swabbing tube for deep wells, the portion of the tube through which the swab 40 operates being laterally open for the admis-

sion of fluid, a casing at the exterior of and secured to the tubing and inclosing the laterally open portion thereof, the casing provided with a fluid inlet, and a closure for said inlet.

4. A swabbing tube for deep wells, the portion of the tube through which the swab operates being open for the admission of fluid, a casing at the exterior of and spaced from the tubing and inclosing the open portion thereof, the casing having a fluid inlet, and an inlet closure located and operative in the space between the casing and tubing.

5. A swabbing tube for deep wells, the portion of the tube through which the swab operates being open for the admission of fluid, a casing at the exterior of and spaced from the tubing and inclosing the open portion thereof, the casing having a fluid inlet, and a leaf-like spring in the space between 55 the casing and tubing with the free portion of the spring adapted to close said inlet.

6. The combination of well tubing, a packer for shutting off water which enters the well above the packer, the tubing extending beneath the packer and laterally perforated for the admission of gas and water, a swabbing tube within and spaced from the first mentioned tubing, a foot valve for the swabbing tube, a swab operative within the 65 swabbing tube, and a valve-controlled lateral fluid inlet in that portion of the swabbing tube through which the swab operates.

In testimony whereof I affix my signature in presence of two witnesses.

CHARLES M. HEETER.
